UNITED STATES PATENT OFFICE.

WILLIAM G. COUGHLIN, OF PHILADELPHIA, PENNSYLVANIA.

RAIL-HOLDING DEVICE AND ANTICREEPER.

Application filed October 14, 1926. Serial No. 141,586.

This invention relates to rail fastenings and particularly to fastenings for preventing separation and creep between rail and tie.

When the wheels of a railway train pass over the rails the action thereupon is to cause a depression in the rails immediately beneath the point of contact with the wheels, due to some extent to the compression of the rails, to some extent to the bending of the rails between the ties, but principally to the depression of the roadbed and accompanying sinking of the ties. The ties at either side of the point of contact or point of load application have smaller unit loads and hence sink less than the tie or ties nearest the point of load application. This being true, the edge of the tie toward the depression acts as a fulcrum for the rail causing it to cant the tie or pull the spikes therefrom; and the tie as a whole acts as a fulcrum causing the rail beyond it to lift, which raises the adjacent tie or pulls the spikes from it. The usual happening in both cases is the starting of the spikes which leaves the track in a dangerous condition for subsequent traffic.

There is also a tendency of the rails to creep over the ties due to lengthening and shortening of the rails with changes of temperature, endwise push upon the rails by the driving wheels of locomotives, downgrade movement of the rails from gravitational forces coupled with the beat of wheels, and various other causes.

It is, therefore, one object of this invention to provide improved means for preventing separation of rail and tie. It is another object to provide improved means for preventing creep of the rail over the tie. A novel feature of this invention is the provision of a single device for preventing both lifting and creeping of the rails. Another feature is the provision of such a device which is efficient in service, easy to apply, and inexpensive to manufacture.

Other objects and features of novelty will be apparent from the following description taken in connection with the drawings, in

50 which:—

Figure 1 is an elevation of the device showing the rail in section;

Figure 2 is a plan view of the Figure 1 construction;

Figure 3 is a detail view of the fastening member;

Figure 4 is a plan view of a modified construction;

Figure 5 is a sectional elevation taken on line 5—5 of Figure 4; and

Figure 6 is a sectional elevation similar to Figure 5 but showing another modification.

Figures 1 to 3 show one form of fastening device which is adapted to be used with a tie plate 10 having flanges 11 along the sides of a crosstie. A clip or fastening member 12 has lugs 13, 14 forming a jaw engaging a base flange of the rail, the upper lug being formed with a sloping under surface to fit the top slope of the flange. The base or inner end of the jaw is enlarged by undercutting the lugs as shown at 15 to permit the jaw to be wedged upon the flange. As shown in Figures 2 and 3, the lug 14 is bent at an angle to the lower lug or, taken 75 in relation to the rail, the lug may be said to be bent at an acute angle to the axis of the rail or at an angle to a plane perpendicular to the rail.

The clip has a resilient tail or projection 80 16 of such dimensions and character as to oppose the lift of the rail. This appendage engages a seat or abutment which is bent from the tie plate or otherwise suitably secured with respect to the tie. The seat or 85 abutment 17 slopes downwardly away from the rail so that the projection 16 will wedge thereagainst upon upward movement. A second projection 18 is formed on the clip. This projection is rigid and is disposed beneath a stop 19 rigidly secured to the tie. The stop is shown as being formed on the tie plate. The projection 18 may fit directly against or lie a small distance below the stop 19. When the left base flange of the 90 rail as shown in Figure 1 tends to lift due to lifting or overturning the jaw grips it and carries the whole clip including the spring projection 16 upward. The projection 16 soon wedges beneath the sloping seat 17 and 100 stops the movement by rigid projection 18 comes into contact with the stop 19 to prevent further movement.

When the projection 18 engages the stop 105 19 in operation the clip acts as a lever turning about stop 19 and the projection 16 limits the movement in resilient fashion by flexing due to the engagement of its outer end with the seat 17. In case the projection 110 16 should break, the projection 18 will still engage stop 19 and act as a safety device.

The clip is secured to the tie by a gauge adjusting plate 20, bolt 21, and nut 22. The bolt may pass through the tie plate and tie to hold the tie plate rigidly thereon or the bolt may pass through the flange of the tie plate only, in which case, the tie plate will be secured in any desired manner upon the tie.

The clip is curved or bent in the center 10 in order that it may be lengthened by straightening to cause it to wedge between the seat or abutment 17 and the flange of the rail. Straightening may be accomplished either by pulling up the nut on bolt 15 21 or by hammering the clip before putting it into position.

The action of the clip to prevent overturning or lifting of the rail has been explained. The clip not only serves this purpose but prevents longitudinal creeping of the rail in one direction as well. Upon initial longitudinal movement of the rail against the outbent end of the lug 14 of the clip, the lug will tend to straighten and 25 wedge tightly against the rail flange. Then since the clip is rigidly fastened to the tie, it will prevent creep between rail and tie. To stop creep in the other direction it is only necessary to use a clip on the other side 30 of the tie. In the drawings the second clip is placed diagonally opposite the first but it will be obvious that if the clips and their lugs are bent on the opposite side the clip may be used in either or both of the other 35 diagonally opposed positions.

A modification of this device is shown in Figures 4 and 5. Here a lug or stop 25 is disposed with its inner vertical edge a sufficient distance from the base flange of the rail to permit the rail to seat upon a tie or if desired, upon a tie plate as illustrated in Figures 4 and 5. The construction shown in Figure 5 is particularly adapted to be used in conjunction with poured concrete ties 40 though obviously also adapted to be used with other types of ties. Here the lug or stop has a shank 26 passing through the tie plate (if used) and into the tie. A bolt 27 passes through the tie, preferably near the 45 neutral axis to prevent undue weakening of the tie as a beam, and through a hole in the shank to hold the lug in position. The lug suitable for use with the present modification may be struck up from the tie plate 50 as shown in Figure 6 in connection with a further modification presently to be described. The lug has a curved notch 28 on one side and a curved edge 29 on the other side, both curves being struck from the same center.

A clip 30 of spring metal is formed with an opening or slot 31 of proper size to closely fit against the curved portion 29 of the lug or stop 25 when the clip is in operative position. One end of the clip is curved

as at 32 and fits between the stop and the rail flange. The clip has a boss or ridge 33 making contact with the rail flange to prevent creeping of the rail, the clip being so tightly wedged in position upon the rail as 70 to provide great friction resisting creeping of the rail. The reaction to creeping in either direction is taken by the lug since the clip straddles the lug.

To position the clip it is held with projection 34 thereof in a nearly vertical position, the slot 31 passed over the stop 25, the curved end 32 engaged in the curved notch 28 and the clip rotated into the position shown in Figure 5. In this position so the outer end of the slot fits against the curved surface 29 of the stop and prevents the curved end coming out of the notch. The outer end of the clip may be fastened down if desired to prevent unwarranted removal of the clip but is not necessary for successful operation of the clip since the point of contact with the lug is beyond the point of contact with the rail flange thus insuring that the flexible projection 34 will 90 rest upon the tie or tie plate.

This device is preferably used on the inside of the rail, any desired device being used to retain the rail on the outside, such as spikes or a ridge 35 on the tie plate as 95 shown in Figure 4, though it may be used on either side of the rail with equal effectiveness.

Figure 6 shows another modification in which the lug or stop 36 has a notch 37 100 with an undercut seat 38, a spring clip 39 has a slot 40 longer than the lug to allow the clip to be wedged into position. The bent end 41 of the clip has a ridge 42 which snaps into position in the seat 38. A ridge or boss 105 43 on the main portion of the clip serves the purpose of preventing longitudinal creep as explained in connection with boss 33 of the previously described modification.

The clip is placed in position by putting 110 the slot 40 over the stop 36 and driving the bent end 41 away from the rail web until the ridge 42 snaps into the seat 38.

As in the other form this clip is held securely because the point of contact with the 115 lug is beyond the point of contact with the rail flange. The outer end may likewise be secured if desired to prevent unwarranted removal of the clip.

In case a tie of old rail of other metal is 120 employed, lugs suitable for use with either the modification shown in Figure 5 or that described with Figure 6, may be struck up from the flanges of the tie itself.

It is to be understood that the invention 125 is not to be limited to the embodiments illustrated, but may assume various other embodiments if within the scope of the appended claims.

Having thus described the invention, 130

what is claimed as new and desired to be secured by Letters Patent is:

1. A device of the character described, comprising in combination, a tie, a rail supported thereon, a clip mounted on the tie having a face engaging the base of the rail adapted to resist longitudinal movement of the rail, said clip also having a resilient appendage to resist lifting of the rail from the tie.

2. A device of the character described, comprising in combination, a tie, a rail supported thereon, a clip having a face to press upon the rail base, a stop rigid with the tie above the clip, and a seat rigid with the tie, said clip having a resilient appendage engaging said seat to press the face toward the rail base to prevent separation of the rail from the tie, and said clip face by engagement with the rail base also causing resistance to longitudinal creep of the rail.

3. A device as claimed in claim 1 in which said clip is secured upon a tie plate rigidly mounted on the tie.

4. A device as claimed in claim 2 in which said clip is secured upon a tie plate rigidly mounted on the tie.

5. A device as claimed in claim 2 in which said clip is secured upon a tie plate rigidly mounted on the tie, said stop being formed from the material of the tie plate.

6. A rail fastening device comprising in combination, a tie, a rail thereon, an upstanding stop member secured to the tie, a clip beneath the stop member having a bearing surface engaging the base flange of the

rail to hold the rail to its seat, said surface being provided with a boss to grip the rail upon slight axial movement thereof, and a resilient projection on the clip having its end carried by the tie to hold said bearing surface upon the rail flange.

7. A rail fastening device, comprising in combination, a tie, a rail thereon, an upstanding overhanging stop, a bolt through the tie and the lower end of the stop securing the stop to the tie, a clip between the stop and a base flange of the rail, said clip having a curved end fitting beneath the stop and engaging the base flange of the rail to prevent overturning and longitudinal creep, and an opening passing over the stop and closely fitting the same to prevent the curved end from moving out of position except upon rotary movement of the clip.

8. A rail fastening device comprising in combination, a tie, a tie plate rigidly mounted thereon, a rail carried by the tie plate, said tie plate having an upstanding overhanging stop member, a clip having an opening passing over the stop, a bent portion engaging said stop and the base flange of the rail to hold the rail to its seat and to prevent longitudinal creep, and a resilient projection resting on the tie plate, said clip being put in position by passing the stop through its opening and sliding the bent portion under the overhanging stop.

In testimony whereof I hereunto affix my signature.

WILLIAM G. COUGHLIN.
